United States Patent Office.

DANIEL T. ROBINSON, OF BOSTON, MASSACHUSETTS.

Letters Patent No. 61,871, dated February 5, 1867.

IMPROVEMENT IN MACHINE FOR CUTTING STRAW AND HAY.

The Schedule referred to in these Letters Patent and making part of the same.

TO ALL TO WHOM THESE PRESENTS SHALL COME:

Be it known that I, DANIEL T. ROBINSON, of Boston, in the county of Suffolk, and State of Massachusetts, have invented a new and useful implement for Cutting Hay, and do hereby declare the following to be a full, clear, and exact description thereof, reference being had to the accompanying drawings, making part of this specification, and in which—

Figure 1 is a top view or plan.

Figure 2, a vertical and central section; and

Figure 3, an end elevation of my invention.

My present invention is an adaptation, or application to the purposes of cutting hay, of a greater portion of the device for which Letters Patent of the United States were granted to me on the 24th day of April, 1866, for an implement for cutting tobacco.

As represented in the accompanying drawing, A is the frame, and B the box or chute for receiving the hay to be fed along towards the cutting mechanism; this mechanism consisting of a bent or bell-crank lever, a, pivoted at its angle to the inner face of a metallic frame or bracket, b, applied to the front end of the box or chute B, as represented. The lower extremity of the lever a is jointed to one end of a knife, c; the opposite end of such knife being jointed to the lower extremity of a swinging arm, d, pivoted to the inner face of the bracket b, and in a plane with the lever a. The longer arm e of this lever extends some distance beyond the frame of the implement, and serves as a handle to impart the necessary movements to the knife. A second and stationary knife, f, is applied to the bracket b, and so as to work in conjunction with or against the inner face of the knife c, as shown in fig. 2 of the drawings. The inner face of the bracket b serves as an abutment or bearing surface for the lever a and arm d to work against, to prevent lateral separation of the knives during the process of cutting hay. A spring, g, is to be applied to any suitable part of the bracket, the free end of such spring pressing against the under side of the arm e of the lever a, and serving to throw such arm upward after each depression of it, thus relieving the operator of much of the worst of the labor, that is, of raising the lever. The operation of the machine will be so readily understood, by those conversant with hay-cutters, that further description is considered unnecessary.

I claim the special adaptation to the purposes of a hay-cutter, of the mechanism before described, consisting of the lever a, swinging arm d, knives c and f, and spring g applied to and supported by the bracket b, substantially as described.

DANIEL T. ROBINSON.
